UNITED STATES PATENT OFFICE.

EDWARD M. GERRY, OF NORWOOD, OHIO, ASSIGNOR TO THE BULLOCK ELECTRIC MANUFACTURING COMPANY, A CORPORATION OF OHIO.

OIL-SWITCH.

No. 891,833.

Specification of Letters Patent.

Patented June 30, 1908

Application filed May 10, 1905. Serial No. 259,789.

To all whom it may concern:

Be it known that I, EDWARD M. GERRY, a citizen of the United States, residing at Norwood, in the county of Hamilton and State of Ohio, have invented certain new and useful Improvements in Oil-Switches, of which the following is a full, clear, and exact specification.

My invention relates to switches or circuit-breakers for electrical circuits and particularly to switches having their contacts in a relatively non-conducting liquid, such as oil.

It has been the custom in oil switch and oil circuit-breaker design to operate on the principle of instantly breaking the circuit by the operation of the switch or circuit-breaker. In high voltage work this sudden interruption of a large flow of current presents a number of objectionable features, among them being the necessarily high rupturing duty which the switch has to perform, and also the production of a surging in the distributing system which is extremely undesirable.

The object of my invention is to produce an oil switch or circuit-breaker, particularly adapted for use in connection with high voltage systems, said switch or circuit-breaker being adapted to reduce the current in the circuit to a comparatively small amount before the final break and thereby make the arc-rupturing duty of the switch very low, and prevent surging on the system.

A further object of my invention is to increase the arc-rupturing capacity of the switch.

My invention therefore consists of an oil switch or circuit-breaker provided with means for introducing a resistance or other current reducing means into the circuit as the switch or circuit-breaker opens and before the final break in the circuit.

The invention further consists of combinations of elements especially adapted to perform the desired functions, as will be hereinafter described and particularly pointed out in the appended claims.

In the accompanying drawings which illustrate the preferred embodiments of my invention, Figure 1 is a plan view of one form of the switch, the cover plate being shown partly broken away; Fig. 2 is a section on the line 2--2 of Fig. 1; Fig. 3 is a plan view of a modified form of the improved switch; and Fig. 4 is a sectional view on the line 4--4 of Fig. 3.

Referring now to Figs. 1 and 2, the tank 5, to which is fastened the cover plate 6 by means of the pivoted bolts 7 and the nuts 8 or in any other desired manner, is partly filled with oil or other non-conducting fluid, 50 preferably to the level indicated by line 9. Suspended from the cover plate 6 by means of the bolts 10 is a supporting plate 11 preferably constructed of insulating material. This plate 11 carries the insulating supports 65 12, 13, 14, and 15 grouped as shown in Fig. 1. The supports 13 and 15 preferably project completely through the supporting plate 11 (as shown in section Fig. 2) and each carries at its lower end a contact segment 16 and at 70 its upper end a clip 17, the clip 17 and contact segment 16 being electrically connected by the conductor 18 passing completely through the insulating support. The supports 12 and 14 project from one side of the 75 plate 11 and each carries at its upper end a clip 17. The clips 17 support the resistance sections 19 and 19^a, resistance section 19 being connected in a zig-zag fashion between the clips 17 on the supports 13 and 14 for one 80 side of the circuit and the section 19^a being connected between the clips on supports 12 and 15 for the other side of the circuit. The contact segments 16 are adapted to be bridged by the bridging member 20. This 85 member 20 is mounted upon the rock shaft 21, but is insulated therefrom by block 22. The shaft 21 projects upwardly through the cover plate 6 and has attached to its upper end the operating crank 23 to which is pivoted the link 24 connected to a remote control mechanism, not shown. The crank 23 may be replaced by an operating handle if so desired. The end contact segments 16^a and 16^b are connected to the terminal leads 95 25 and 26 respectively, the lead 25 passing through insulating bushing 27 and lead 26 passing through bushing 27^a in the cover plate 6. One end of the resistance 19 is connected to the lead 25 at 30 and its other end 100 is in electrical communication with the contact segment 16^c. The resistance 19 is connected at intermediate points to the contacts 16 located on an arc of a circle between 16^c and 16^a. The supports 14 and their clips 105 merely act to support the sections of the resistance between adjacent contact segments. One end of resistance 19^a is connected to lead 26 at 31 and its other end is in electrical connection with contact segment 16^d. 110

Said resistance 19^a is connected at intermediate points to contacts 16 located in an arc of a circle between 16^b and 16^d. The switch in these figures is shown in its closed position with the bridging member 20 bridging the contact segments 16^a and 16^b and short-circuiting the resistances 19 and 19^a. The current enters through lead 25, passing through 20 and out through lead 26. As the shaft 21 is rotated in a counter-clock-wise direction, the member 20 moves over the segments 16 and gradually and automatically introduces the resistance into the circuit before the final break, which takes place when member 20 moves off the contact segments 16^c and 16^d in a counter clock-wise direction. Just before the final break the circuit may be traced as follows: entering lead 25, passing through resistance 19 in a zig-zag direction between supports 13 and 14, through contact segment 16^c, bridging member 20, contact segment 16^d, resistance 19^a in a zig-zag direction between supports 15 and 12, and then out through lead 26.

In the modification illustrated in Figs. 3 and 4, the tank containing the oil and switch contacts is of slightly different shape from the form just described, and the bridging member has a vertically reciprocating movement. The tank 5^a is fastened to the cover plate 6^a by means of the bolts 7 and nuts 8. The supporting plate 11^a is arranged in a vertical plane and is mounted upon the lugs 32 preferably formed integral with the cover plate 6^a. The plate 11^a carries a plurality of insulating supports 35 arranged in two vertical rows. The supports 35 pass completely through the plate 11^a and each carries at one end on one side of the plate a contact segment adapted to be engaged by a vertically movable bridging member 20^a. These contact segments are designated 36^a to 36^f inclusive, and 37^a to 37^f inclusive. Each of the supports 35 carries at its opposite end on the other side of the plate 11^a a clip 17^a, and between these clips is strung in zig-zag manner the resistance 38. The contact segment and clip carried by a single support 35 are connected electrically by conductor 39, which passes completely through the support. The lead 25^a which passes through the insulating bushing 27^b in the cover plate is connected with the lower contact segment 36^a. The lead 26^a which passes through the bushing 27^c in the cover plate is connected to the contact segment 37^a. The resistance 38 is also connected with these leads at 38^a and 38^b. The bridging member 20^a is mounted upon the cross bar 40. This cross bar is carried by the plungers 41 and 42 which pass through the cover plate 6^a and are connected by the cross head 43 to which any desired operating mechanism may be attached.

The switch in Figs. 3 and 4 is shown in its

open position. In its closed position the bridging member 20^a connects the contacts 36^a and 37^a and the circuit is completed through lead 25^a, member 20^a and lead 26^a. As the member 20^a is moved upward the resistance 38 is automatically cut into circuit and when the member 20^a bridges contacts 36^f and 37^f just before the final break, the circuit may be traced as follows: from lead 25^a, to contact 36^a, thence through part 75 of resistance 38 in a zig-zag direction, through clips connected with contacts 37^b, 36^c, 37^d, 36^e and 37^f, through bridging member 20^a to contact 36^f, thence through the remainder of resistance 38, through clips 80 connected with contacts 37^e, 36^d, 37^c, 36^b, 37^a, and out through lead 26^a.

In the appended claims I aim to cover all changes and modifications of my invention and do not limit myself to the specific mechanism shown and described.

Having thus described my invention, what I claim as new and desire to secure by Letters Patent is:—

1. In an oil switch or circuit-breaker, a tank containing oil, a supporting plate mounted within said tank, insulating supports mounted on said plate, contact segments mounted upon said supports on one side of said plate, a bridging member adapted to engage said contact segments successively, and resistance sections mounted upon said supports on the other side of said plate and electrically connected to said contact segments.

2. In an oil switch or circuit-breaker, a tank containing oil, a supporting plate mounted within said tank, insulating supports mounted on said plate, contact segments mounted upon said supports on one side of said plate, a bridging member adapted to engage said contact segments successively, resistance sections mounted upon said supports on the other side of said plate and electrically connected to said contact segments, and means projecting from said tank for operating said bridging member to include said resistance sections in circuit as the switch or circuit-breaker is opened.

3. In a switch or circuit-breaker, a supporting plate, insulating supports mounted on said plate, contact segments mounted upon said supports on one side of said plate, a movable member arranged to engage said contact segments successively, resistance sections mounted upon said supports on the other side of said plate and electrically connected to said segments, and a tank containing oil in which said contact segments are immersed.

4. In a switch or circuit-breaker, a supporting plate, insulating supports mounted on said plate, contact segments mounted upon said supports on one side of said plate, a movable member arranged to engage said

contacts successively, resistance sections mounted upon said supports on the other side of said plate, conductors within said supports and electrically connecting said contact segments and said resistance sections, and a tank containing oil in which said contact segments are immersed.

In testimony whereof I affix my signature, in the presence of two witnesses.

EDWARD M. GERRY.
